FUSE SETTING APPARATUS FOR SHELLS

Valentine Pearce Harvey, Deptford, London, England, assignor to Molins Machine Company, Limited, London, England

Application October 14, 1940, Serial No. 361,147
In Great Britain March 23, 1939

11 Claims. (CL 86—23.1)

This invention concerns improvements in or relating to fuse setting apparatus for shells, such for example as 3.7 inch shells such as are used with anti-aircraft guns.

The fuses which are to be set by the apparatus according to the present invention are of the kind having a fixed and a movable fuse-element, the latter being rotatable about the longitudinal axis of the shell with which the fuse is connected, the setting of the fuse being determined by the relative angular positions of the fixed and movable elements. Such fuses will be referred to hereinafter as "fuses of the kind described." The fixed and movable fuse-elements are provided with shoulders or abutments, and an abutment on the fixed fuse-element will be called "a fixed abutment," whilst an abutment on the movable fuse-element will be called "a movable abutment." These abutments are provided to enable pawls or other members in the fuse-setting apparatus to register therewith for the purpose of setting the fixed and movable fuse-setting elements in the desired angular relationship.

Where the term "locating element" is used herein it shall be taken to mean the said pawls or the said other members.

The present invention refers to fuse-setting apparatus of the kind having locating elements mounted in two holders rotatable about an axis coincident with the axis of a shell the fuse of which is to be set, the locating elements being adapted to engage with the fixed and movable abutments and to move the movable element of the fuse relatively to the fixed element. Such a fuse-setting apparatus will be referred to herein as a "fuse-setting apparatus of the kind described."

According to the present invention there is provided fuse-setting apparatus of the kind described, said apparatus having means for causing relative rotary movement between the two said holders, said means comprising a differential gear, driving means operative to drive one sun gear wheel of said differential gear, the second sun gear wheel being arranged to drive one only of said holders in one direction, rotation of the planet carrier of the differential being arranged to drive the second of said holders in the opposite direction and a train of gear wheels coupling one holder to its driving source in the differential.

Further, according to the invention there is provided fuse-setting apparatus of the kind described, said apparatus having means for causing relative rotary movement between the two said

holders, said means comprising a differential gear, driving means operative to drive one sun gear wheel of said differential gear, one of the holders being operatively connected for positive drive in one direction by the second sun gear wheel, rotation of the planet carrier of the differential gear being arranged to drive the second of said holders and a train of gear wheels coupling one holder to its driving source in the differential, gear wheels of said train being mounted for orbital movement about the axis of rotation of the sun gear wheels to alter the relative angular positions of the said holders and means to hold the said train in any desired orbital position.

15 Preferably each of said holders is capable of rotating 360 degrees, the sum of the total angles through which the two holders turn is at least equal to 720 degrees, and means is provided to stop rotation of the driving or first said sun gear wheel of the differential when the latter has reached a predetermined angular position. The differential gear may be of the bevel gear type, and the train of gear wheels preferably comprises a gear wheel fixed to the planet gear wheel car-

20 rier of the differential and meshing with one of two gear wheels on a counter-shaft, the other of said two gear wheels being arranged to mesh with the gear wheel fixed to the said second holder. Gears of said train of gears may be mounted

25 so as to be movable through an arcuate path about the axis of rotation of the sun gears to alter the relative angular positions of the locating elements. The counter-shaft may be journalled in a worm wheel which has its axis concentric with that of the sun gear wheels of the differential whilst a hand operated worm is arranged to mesh with and rotates said worm wheel to cause the counter-shaft to move in an orbital path. Preferably a fixed stop member is mounted

30 on a fixed part of the fuse setting apparatus and is located in the path of a movable stop member carried on a movable part of the fuse setting mechanism, whereby the said mechanism is brought to rest by the said stops engaging one

35 another, when the first said sun wheel of the differential has reached a predetermined angular position. A spring loaded catch element arranged to hold the movable stop between the catch and a fixed stop may be located in the path

40 of the movable stop member in front of the fixed stop member, the catch element being compressible by the movable stop only when the latter is moving towards the fixed stop. Means mentioned below may be provided to prevent operation of

45 the apparatus until a shell is properly located

therein. Said means preferably comprises a movable control member adapted to move between a position to engage and retain against movement, a movable element of the fuse setting mechanism and another position clear of such mechanism, an actuating lever coupled to move with a cushioning device for the shell and a lost motion connection between the actuating lever and the control member, whereby the control member is adapted to be moved by the actuating lever to such clear position when a shell is properly located in the apparatus. Preferably a resilient member urges the control member towards the position to engage the said movable element of the fuse setting mechanism. The actuating lever may be adapted to engage the catch element to withdraw the latter from the path of the movable stop member after a shell is withdrawn to allow the fuse setting mechanism to be reset. Manual means may be provided for moving the control member to the said clear position at will.

Fuse setting apparatus made in accordance with the present invention will now be described by way of example with reference to the accompanying drawings, in which:

Figure 1 is an end elevation of a fuse setting apparatus.

Figure 2 is a sectional side elevation partly on the line A—A, Figure 1, and partly on the line B—B, Figure 1. Everything to the left of and including the stop 68 is a section on the line A—A, and the remainder is a section on the line B—B.

Figures 3 and 4 show the pawls used for powder and mechanical fuses respectively.

Figure 5 is a fragmentary view in the direction of the arrow C, Figure 2.

Figure 6 is a side elevation on an enlarged scale of certain gearing elements shown in Figure 2.

Like reference numerals refer to like parts throughout the specification and drawings.

The fuse setting apparatus has a casing 1 to which is attached a part 2 and a part 3 which is removable to enable certain parts to be changed. This part 3 is provided with a hollow support which is adapted to receive the nose of the shell. A concave roller 4 mounted on a bracket 5 pivoted at 6 to the hollow support is arranged in front of the hollow support. In Figure 2 a shell 7 is shown in position in the fuse setting apparatus. The nose of the shell is seen to be pressing against a slideable member 8 of a cushioning device. The slideable member 8, which has been displaced to the left in Figure 2 by the shell, has an enlarged portion which fits within a sleeve 9. A compression spring 10 acting between this enlarged portion and the sleeve 9 offers a resistance to the displacement mentioned above. A lever 11 pivoted on a pin 12, has an aperture through which an extension 13 of the slideable member 8 extends. A collar 14 mounted on the slideable member 8 enables the lever 11 and member 8 to move one another at the appropriate times. The lever 11 is pivotally connected near its lower end to a rod or arm 18 attached to the piston of a dashpot 15, the dashpot being provided to resist clockwise movement of the lever 11. A tension spring 16 anchored to a pin 17, which is also the pivot pin to the dashpot 15, tends to turn the lever 11 in an anti-clockwise direction. From the description of the apparatus given so far it will be seen that on the insertion of a shell the member 8 is moved bodily towards the left hand side of Figure 2, and the collar 14 turns the lever

11 in a clockwise direction against the resistance of the dashpot 15. The parts are so arranged that on the insertion of a shell the spring 10 is first compressed, and when the member 8 has been moved sufficiently far to cause the ring 14 to engage the lever 11, then the resistance of the dashpot is added to that of the spring 10. An adjustable stop 19 controls the extent of movement of the lever in a clockwise direction. The dashpot 15 is mounted in the lower part of the apparatus and is arranged to be totally submerged in oil held in the casing 1.

The sleeve 9 previously referred to is mounted so as to be capable of rotating. To the right hand end of the sleeve 9, as seen in Figure 2, is bolted a ring 20, which acts as a holder for pawls which are adapted to engage the notch in a fuse ring 21 of the shell. A second pawl-ring 22 having pawls to engage abutments in a fuse ring 23 of the shell is bolted to a hollow rotatable member 24 which encircles the hollow sleeve 9. Roller bearings 25 and 26 are provided between the rotatable members 9 and 24, and the outer surface of the latter is supported by ball bearings 27 and 28. The outer ball race of the ball bearing 28 is mounted on a fixed part of the casing of the fuse setting apparatus.

The pawl rings 20 and 22 are arranged in the construction being described to set a powder fuse. When it is desired to set a clockwork fuse the pawl rings are changed and rings having pawls suitable for engaging the abutments or notches on the clockwork fuse are substituted. Figure 3 shows a part of a pawl-ring with pawls 220 suitable for a powder type fuse. The pawls are slideable radially and are spring urged inwardly to engage the fuse-ring. Figure 4 shows a part of a pawl-ring with pawls 221 suitable for the clockwork type of fuse. Except for the shape of their notch engaging portions, pawls 221 are similar to the pawls 220. To change the pawl rings, the hollow support 3 is removed and the pawl-ring 22 is unscrewed from the rotatable member 24. Next, a spacing ring 29 is removed and then the pawl-ring 20 is unscrewed from the hollow support 9. The new pawl-rings are then substituted.

The mechanism to drive the pawl-rings is arranged as follows. A toothed quadrant 30, to which is secured an actuating lever 60, meshes with a gear wheel 31 mounted on a shaft 310. The latter carries a split gear wheel 32, which in turn meshes with gear teeth 33 on a sleeve member 34. The right hand end of the sleeve member 34, as seen in Figure 2, constitutes a bevel gear wheel 35 which forms one sun gear of a bevel differential gear. A bevel gear wheel 36 constitutes the other sun gear wheel of this bevel differential gear and is fixed to the rotatable sleeve member 9 to which is secured the pawl ring 20. A planet gear wheel 37 meshes with these two sun gear wheels. The planet gear wheel is carried by a planet carrier 38 provided with gear teeth 39, and a split gear wheel 40 mounted on a counter-shaft 41 meshes with the gear teeth 39. A split gear wheel 42 mounted on the counter-shaft meshes with gear teeth 43 provided on the hollow rotatable member 24 carrying the pawl ring 22. The counter-shaft 41 is journalled in a casing 44 which is mounted on ball bearings 27 and 45 and which is adapted to rotate relatively to the other parts. The inner race of the ball bearing 27 engages the other surface of the rotatable member 24, and the outer race of the ball bearing 27 engages the inner surface of the casing 44. At the

other end, the outer race of the ball bearing 45 engages the inner surface of the casing 44, and the inner race of this ball bearing is mounted on the sleeve member 34. Encircling and fixed to the casing 44 is a worm wheel 46 having split teeth as shown. A worm 47 on a shaft 53 meshes with the worm wheel 46. A bevel gear wheel 48 mounted on a sleeve splined to the shaft 53 meshes with a bevel gear wheel 49 which is mounted on a spindle 490 and is rotated by a hand wheel 50. This hand wheel 50 is also arranged to actuate a follow-the-pointer needle in the receiver 51 from the predictor. The follow-the-pointer needle is operated through the handle 50 by means of a worm 52 mounted on the spindle 490. The worm 52 meshes with a worm wheel 54 mounted on a spindle 55 which is adapted to be coupled to a driving spindle in the receiver 51. It is desirable to limit the amount of movement of the hand wheel 50 in either direction, and in the construction shown this is effected as follows. A gear wheel 56 on the spindle 490 and having 43 teeth meshes with a further gear wheel 57 mounted on an idler shaft 570 and having 42 teeth. Projections 58 and 59 are carried by the gear wheels 56 and 57 respectively and project from hubs 580 and 590 respectively of the gear wheels. These two projections are each arranged to lie in the path of the other in known manner, and thus according to the numbers of the teeth on the gear wheels and the difference between these numbers, the hand wheel can be given a certain number of rotations in each direction before the projections 58 and 59 meet one another and prevent further rotation.

It has already been stated that the quadrant 30 has attached to it a lever arm 60. This lever arm 60 when pulled in a clockwise direction as seen in Figure 1 operates the gears in the direction desired to set the fuse. Mechanism to stop the rotation of the main driving gears when the fuse is set and also to prevent the operation of such gears until a shell is properly located will now be described. A tail piece 61 on the lever 60 passes through an aperture in a catch element 62 slidable in a fixed part 63 of the apparatus. The catch 62 is spring urged towards the right hand side of Figure 2 by a compression spring 64 which acts against the tail piece 61 of the lever 60 and the body of the catch 62. The tail piece 61 also lies between the forks of a control member 65 pivoted on a pin 66 and spring urged by a compression spring 67 to engage the quadrant 30. A fixed stop member 68 is mounted on a fixed part of the apparatus and a moving stop member or lug 69 is provided on the gear wheel 32.

The quadrant 30 is not shown in the proper position in Figures 1 and 2 relative to the other gear wheels. In the position shown in Figures 1 and 2 the stop 69 is shown held between the fixed stop 68 and the catch 62 so that the gear wheel 32 cannot be rotated in either direction. That then represents the position of the parts after a fuse has been set. The quadrant 30 in that case would naturally be much higher up than is shown in the figures, since the lever arm 60 would be depressed and not in the up position shown in Figure 1. The arrangement of these parts can be determined from the following description. Assume the apparatus has just set a fuse, so that the parts with the exception of the quadrant 30 are in the position shown in Figures 1 and 2. On withdrawal of the shell the slidable member 8 will move to the right as seen in Figure 2, and the lever 60 will move in an anti-clockwise

direction. This anti-clockwise movement of the lever will cause the lever 60 to withdrawn the catch 62 from the path of the stop 69. The tail 61 of the lever 60 does not push the control member 65 over to the left owing to the large gap provided. The catch 62, however, having been withdrawn, it is now possible to rotate the lever 60 in an anti-clockwise direction to reset the apparatus. When this is done, the quadrant 30 will move down so that a detent 70 on the control member 65 will engage the top surface 71 of the quadrant 30. Thus as soon as the lever arm 60 is returned to the position shown in Figure 1, the control member 65 will make it impossible to move the lever arm 60 until another shell is properly located in the fuse setting apparatus. A manually operable plunger 72 is provided for releasing the quadrant 30 from the control member 65 if it is desired to operate the mechanism without a shell being in position. A compression spring 73 holds the plunger away from the control member 65. On insertion of a subsequent shell the tail piece 61 will move to the right hand side in Figure 2. Owing to the lost motion connection between this tail piece 61 and the forks of the control member 65 the latter will not be moved clear of the quadrant 30 until the very last moment, that is to say, at the moment when the shell is properly located. The catch 62 will, of course, have been moved forwardly to lie in the path of the movable stop member 69 on the gear 32. The stop member 69, however, will not then be in the position shown in Figure 2, since the mechanism, as has been mentioned before, has been reset. As shown in Figure 2, the face of the catch 62 is arranged to slope so as to enable the stop 69 to depress the catch 62 only when the stop is moving towards the fixed stop 68, that is to say, during the setting operation.

The apparatus is now ready to set the fuse, and to do this the lever arm 60 as seen in Figure 1 is pulled down in a clockwise direction. The gears will be brought to rest as soon as the stop 69 has moved past the catch 62 and engaged the fixed stop 68. It will then be impossible to move the lever arm 60 in either direction.

In the example shown the gear wheels are so arranged that the sleeve member 34 and its sun gear wheel 35 (that is, the driving sun gear of the differential) move through just over two complete revolutions in order to ensure that the notches in both fuse rings will be engaged in whatever angular positions they may be.

When, in a fuse setting apparatus according to this invention, it is desired to ensure that pawls in each of the pawl rings will, during a setting operation, engage the fuse abutments (without the necessity of rotating or otherwise previously angularly positioning the shell), irrespective of the relative positions of these abutments, to one another and to the pawls on the insertion of a shell into the apparatus, then the pawl ring for the fixed abutment must be capable of rotating 360°, if necessary to engage the fixed abutment, and will cease to rotate when the fixed abutment is engaged, even though that be earlier than 360°. In all such cases, however, the sum of the total angular movements of the two pawl rings must always be at least equal to 720° to permit both pawl rings to rotate 360° if that be necessary to locate their respective abutments. In the example being described this sum is 723° and the sun gear 35 is arranged to rotate approximately 2.01 revolutions. This then ensures that both the

fixed and movable abutments will always be engaged and the latter positioned where desired.

It is necessary of course, that the angular relationship between the pawl rings 20 and 22 corresponds to a reading indicated by the follow-the-pointer needle in the receiver 51 at the time when the stop 69 is locked between the catch 62 and the stop 68. This is, however, a simple matter of adjustment.

From the foregoing it can be seen that when the lever arm 60 is pulled down, the driving sun gear 35 rotates. The planet gear wheel 37 rotates about its own axis, thus rotating the second sun gear 36; the pawl ring 20 is thereby rotated through the rotatable sleeve 9. Assuming that the pawls in the pawl ring 20 are not in engagement with the notch in the ring 21, and the resistance to rotation imposed on the gear 39 is greater than that imposed on the gear 36, the latter will rotate, whilst the planet gear 37 will merely rotate about its own axis without moving orbitally. Thus the pawl ring 20 will continue to move until the pawls in the pawl ring 20 engage the notch in the fuse ring 21. Then, whether the ring 21 is a fixed or movable ring, enough resistance will be set up to cause the planet carrier 38 to rotate so that the planet gear wheel 37 moves orbitally. Rotation of the planet carrier 38 causes the gear wheel 39 to rotate, and this in turn rotates the gears 40, 42 and 43, the latter being fixed to the member 24 which carries the second pawl ring 22, which is rotated until the pawls thereof engage the notch in the fuse ring 23. The pawl ring 22 is, as can be seen, coupled to the planet carrier 38 of the differential, and the carrier 38 is, in the example shown, the driving source in the differential for the pawl ring 22. When the notches in the ring 23 are engaged, the further rotation of the pawl rings will depend upon which is the fixed fuse ring. If the ring 23 were the fixed fuse ring, then the resistance to rotation offered by the ring 23 would be greater than the resistance to rotation offered by the ring 21, and consequently in such a case movement from the quadrant 30 would be transmitted through the sun gear 36. The moving pawl ring would then continue to rotate until the mechanism is brought to rest by the engagement of the stop 69 with the fixed stop 68. In the example shown in the drawings the fuse is of the powder type, and in such a case the fixed ring is the ring 21. In that case, therefore, when the pawls have engaged the notches, the pawl ring 22 is the one which will continue to rotate.

The pawl rings 20 and 22 rotate in opposite directions, and the gear wheels are so proportioned that the pawl ring 22 when moving will be moving at the same angular velocity as the pawl ring 20 had previously moved in the opposite direction. When, however, the driving sun gear wheel 35 has rotated through 720° the pawls in the respective pawl rings 20 and 22 will be in the same angular relationship as they were before the driving sun gear had commenced to rotate. In the example described, since the sun gear wheel 35 rotates through 2.01 revolutions, the relative angular positions of the pawls will be slightly different, when the apparatus is brought to rest, from the position in which they were to start with, but as has been mentioned previously, this does not matter provided that the angular relationship of the pawl rings, when the stops 68 and 69 are in engagement at the end of a setting, corresponds to that indicated on the receiver dial by the follow-the-pointer needle.

The angular relationship of the pawls is adjusted by rotating the hand wheel 50 and thus causing the worm wheel 46 to rotate in a clockwise or anti-clockwise direction according to the direction in which the hand wheel 50 is rotated. As can be readily seen, rotation of the worm wheel 46 causes relative angular movement between the pawl rings 20 and 22. Thus the orbital position of the counter-shaft 41 controls the angular relationship of the pawls in the respective pawl rings, and the ultimate setting of the fuse elements will depend upon the orbital position of the counter-shaft 41 and also upon the position in which the driving sun gear 35 is brought to rest.

15 As will be seen from above, it is essential that the driving sun gear 35 should finish up at the same angular position at each fuse setting operation, because it is that final angular position of the driving sun gear 35 which determines whether 20 or not the pawl rings and consequently the abutments on the fixed and movable fuse elements are in the desired angular relationship for a given orbital position of the counter-shaft 41. It is also 25 essential that in all cases the relative angular movement between the two pawl rings must always be the same for a given angular movement of the driving sun wheel 35 of the differential gear.

In the construction described above a different 30 set of pawl rings suitable for a clockwork fuse would be inserted if the apparatus were to set clockwork fuses.

In the construction described and shown in Figure 2, only one bevel gear wheel 48 has been 35 shown, but as shown in Figure 5 another bevel gear 480 is provided. The gear wheels 48 and 480 are arranged one on each side of the bevel gear wheel 49 and mounted on a sleeve 484 keyed to the shaft 53, to provide a simple reverse gear for 40 the worm 47. The bevel wheels 48 and 480 are so arranged that only one can mesh with the teeth of the wheel 49 at a time, see Figure 5, but they are so close to the teeth 49 that it is impossible for the wheel 49 not to be in engagement with either one or the other of the gears 48 and 480. The shaft 53 extends through a bearing in the wall of the casing 1 and a cap 572, Figures 1 and 5, is fitted over the end of the shaft in order to maintain the shaft 53 in either of its axial positions. A spacing member 571 is provided and the cap 572 is tightened up on the end of the shaft. Thus when the spacing member 571 is in position gear wheels 48 and 49 will be in mesh but when the member 571 is taken away and the cap 572 tightened up the wheels 49 and 480 will be in mesh. In this way, when the shaft 53 carrying the wheels 48 and 480 is adjusted axially, it is impossible for the gear wheel 49 to become out of mesh with the train of gears. The purpose of having the gears 48 and 480 on the sleeve 484 is to enable the apparatus to be adjusted to set either type of fuse. The position of the moving and fixed fuse rings on a powder fuse is the reverse to that on the mechanical type of fuse. 55 Consequently when it is desired to alter the angular relationship of the pawl rings for the two types of fuses the worm wheel 46 and counter-shaft 41 must be rotated in the reverse directions. Thus to increase the fuse length for one type of fuse the counter-shaft 41 would have to move in one direction, whereas to increase the fuse length of the other type of fuse the counter-shaft 41 would have to go in the opposite direction. By making the sleeve and the shaft 53 slidably 60 adjustable as mentioned above, the direction of ro-

tation of the shaft 53 can be chosen by causing either the gear wheel 48 or the gear wheel 480 to engage the gear wheel 49, so that the direction of rotation of the hand wheel 50 for increasing or decreasing fuse lengths (as the case may be), will be the same for both types of fuses.

In order to reduce backlash between the wheel 49 and the wheels 48 and 480, the spindle 490 is adjustably mounted. A bush 491 having an external screw thread 492 encircles the spindle 490. A cover 493 has an internal thread which screws over the bush. An internal flange 494 engages a shoulder 495 on the spindle 490. A washer 496 clamped in position by the hand wheel 50 engages the other face of the flange 494. As the cover 493 is rotated in one direction or the other so the flange 494 will carry the spindle 490 with it. Inward movement of the spindle 490 is limited by the flange 494 engaging the end of the bush 491. External teeth 497 cut on the cover 493 engage a knife 498. The latter is arranged so as to be capable of being disengaged from the teeth 497 whenever the cover 493 is to be rotated to adjust the spindle 490.

The split gear wheels 32, 40, 42 and 46 also enable the amount of backlash to be reduced, since the two halves can be adjusted to take up any undue backlash.

It will be observed that an important feature of the construction described is that the sun gear 36 is arranged to drive only the pawl ring 20 and the other pawl ring 22 is arranged to be driven by rotation of the planet carrier 38. In the construction described a train of gear wheels, including the gear wheels 40 and 42 on the counter-shaft 41, couples the pawl ring 22 to its source of driving power in the differential, namely to the planet carrier, and the gear wheel 39 fixed to it. By this construction the counter-shaft is enabled to be moved by the worm-wheel 46 and worm 47 in an orbital path about the axis of rotation of the sun gear wheels 35 and 36. This worm and worm-wheel device comprise means for holding the counter-shaft 41 in any desired orbital position. It is clear that it is only by rotation of the hand-wheel 50 and the worm 47 that the worm-wheel 46 will rotate at all. The orbital movement of the countershaft 41 alters the relative angular positions of the pawl rings 20 and 22 and this can be done at any time and is quite independent of the operation of the remainder of the apparatus. It will be appreciated that in order to obtain the desired adjustment of the relative positions of the pawl rings the ratio of gears 39 and 40 must, in the specific embodiment illustrated herein, differ from the ratio of the gears 42 and 43, since otherwise the orbital displacement of gears 40 and 42 would not affect the position of other gears in the train. It is of course obvious that rotation of the worm wheel 46 will alter the relative position of the pawl rings, and consequently that of the fuse rings even after the wheel 32 is locked against all movement. The arrangement also enables great accuracy of setting to be obtained due to the large diameter of the worm wheel 46 compared with that of even the larger pawl ring 22. Thus any given angular setting is controlled by a relatively long arc of the worm wheel 46. To obtain similar accuracy of setting without providing for orbital movement of certain gears connecting a pawl ring to its driving source in the differential about the axis of the sun gear wheels would require considerable increase in the overall size of the apparatus.

What we claim as our invention and desire to secure by Letters Patent is:

1. Fuse-setting apparatus having rotatable holders, locating elements mounted in said holders and adapted to engage with fixed and movable abutments on the body of a fuse, means for causing relative rotary movement between the two said holders, said means comprising a differential gear, driving means operative to drive one sun gear wheel of said differential gear, means to limit the angular displacement of the sun gear wheel to a predetermined amount, the second sun gear wheel being operatively connected to one only of said holders to drive the same in one direction, the planet carrier of the differential being operatively connected to the second of said holders to drive the same in the opposite direction, one of such operative connections comprising a train of gear wheels coupling one holder to its driving source in the differential, the gearing being such that the sum of the total angles through which the two holders turn is at least equal to 720°.
2. Fuse-setting apparatus having rotatable holders, locating elements mounted in said holders and adapted to engage with fixed and movable abutments on the body of a fuse, means for causing relative rotary movement between the two said holders, said means comprising a differential gear, driving means operative to drive one sun gear wheel of said differential gear, means to limit the angular displacement of the sun gear wheel to a predetermined amount, one of the holders being operatively connected to the second sun gear wheel so as to be driven in one direction thereby, the planet carrier of the differential gear being operatively connected to the second of the said holders to drive the same in the opposite direction, one of such operative connections comprising a train of gear wheels coupling one holder to its driving source in the differential, a pair of gear wheels of said train of different pitch diameter being mounted for orbital movement about the axis of rotation of the sun gear wheels to alter the relative angular positions of the said holders and means to hold the said train in any desired orbital position, the gearing being such that the sum of the total angles through which the two holders turn is at least equal to 720°.
3. Fuse-setting apparatus having rotatable holders, locating elements mounted in said holders and adapted to engage with fixed and movable abutments on the body of a fuse, means for causing relative rotary movement between the two said holders, said means comprising a differential gear of the bevel gear type, driving means operative to drive one sun gear wheel of said differential gear, the second sun gear wheel being operatively connected to one only of said holders to drive the same in one direction, the planet carrier of the differential being operatively connected to the second of said holders to drive the same in the opposite direction, one of such operative connections comprising a train of gear wheels coupling one holder to its driving source in the differential, said train of gear wheels comprising a gear-wheel fixed to the planet carrier and meshing with one of two gear wheels of different pitch diameter on a counter-shaft, the other of said two gear wheels being arranged to mesh with a gear wheel coupled to the said second holder.
4. Fuse-setting apparatus having rotatable holders, locating elements mounted in said hold-

ers and adapted to engage with fixed and movable abutments on the body of the fuse, means for causing relative rotary movement between the two said holders, said means comprising a differential gear of the bevel gear type, driving means operative to drive one sun gear wheel of said differential gear, one of the holders being operatively connected to the second sun gear wheel so as to be driven in one direction thereby, the planet carrier of the differential gear being operatively connected to the second of the said holders to drive the same in the opposite direction, one of such operative connections comprising a train of gear wheels coupling one holder to its driving source in the differential, said train of gear wheels comprising a gear-wheel fixed to the planet carrier and meshing with one of two gear wheels of different pitch diameter on a counter-shaft, the other of said two gear wheels being arranged to mesh with a gear wheel coupled to the said second holder, said two gear wheels being mounted for orbital movement about the axis of rotation of the sun gear wheels to alter the relative angular position of the said holders, and means to hold said two gear wheels in any desired orbital position.

5. Fuse-setting apparatus having rotatable holders, locating elements mounted in said holders and adapted to engage with fixed and movable abutments on the body of a fuse, means for causing relative rotary movement between the two said holders, said means comprising a differential gear of the bevel gear type, driving means operative to drive one sun gear wheel of said differential gear, means to limit the angular displacement of the sun gear wheel to a predetermined amount, the second sun gear wheel being operatively connected to one only of said holders to drive the same in one direction, the planet carrier of the differential being operatively connected to the second of said holders to drive the same in the opposite direction, one of such operative connections comprising a train of gear wheels coupling one holder to its driving source in the differential, said train of gear-wheels comprising a gear wheel fixed to the planet carrier and meshing with one of two gear wheels of different pitch diameter on a counter-shaft, the other of said two gear wheels being arranged to mesh with a gear wheel coupled to the said second holder, the gearing being such that the sum of the total angles through which the two holders turn is at least equal to 720°.

6. Fuse-setting apparatus having rotatable holders, locating elements mounted in said holders and adapted to engage with fixed and movable abutments on the body of a fuse, means for causing relative rotary movement between the two said holders, said means comprising a differential gear of the bevel gear type, driving means operative to drive one sun gear wheel of said differential gear, means to limit the angular displacement of the sun gear wheel to a predetermined amount, one of the holders being operatively connected to the second sun gear wheel so as to be driven in one direction thereby, the planet carrier of the differential gear being operatively connected to the second of the said holders to drive the same in the opposite direction, one of such operative connections comprising a train of gear wheels coupling one holder to its driving source in the differential, said train of gear-wheels comprising a gear-wheel fixed to the planet carrier and meshing with one of two gear-wheels of different pitch diameter on a counter-

55 shaft, the other of said two gear wheels being arranged to mesh with a gear wheel coupled to the said second holder, said two gear wheels being mounted for orbital movement about the axis of rotation of the sun gear wheels to alter the relative angular position of the said holders, and means to hold said two gear wheels in any desired orbital position, the gearing being such that the sum of the total angles through which the holders turn is at least equal to 720°.

60 7. Fuse-setting apparatus having rotatable holders, locating elements mounted in said holders and adapted to engage with fixed and movable abutments on the body of the fuse, means for causing relative rotary movement between the two said holders, said means comprising a differential gear of the bevel gear type, driving means operative to drive one sun gear wheel of said differential gear, the second sun gear wheel being operatively connected to one only of said holders to drive the same in one direction, the planet carrier of the differential being operatively connected to the second of said holders to drive the same in the opposite direction, one of such operative connections comprising a train of gear wheels coupling one holder to its driving source in the differential, said train of gear wheels comprising a gear-wheel fixed to the planet carrier and meshing with one of two gear wheels of different pitch diameter on a counter-shaft, the other of said two gear wheels being arranged to mesh with a gear wheel coupled to the said second holder, a worm wheel which has its axis concentric with that of the sun gear wheels, means journaling said counter-shaft in said worm wheel, and a worm arranged to mesh with and rotate said worm wheel to cause the counter-shaft to move in an orbital path.

65 8. Fuse-setting apparatus having rotatable holders, locating elements mounted in said holders and adapted to engage with fixed and movable abutments on the body of a fuse, means for causing relative rotary movement between the two said holders, said means comprising a differential gear of the bevel gear type, driving means operative to drive one sun gear wheel of said differential gear, means to limit the angular displacement of the sun gear wheel to a predetermined amount, the second sun gear wheel being operatively connected to one only of said holders to drive the same in one direction, the planet carrier of the differential being operatively connected to the second of said holders to drive the same in the opposite direction, one of such operative connections comprising a train of gear wheels coupling one holder to its driving source in the differential, said train of gear-wheels comprising a gear wheel fixed to the planet carrier and meshing with one of two gear wheels of different pitch diameter on a counter-shaft, the other of said two gear wheels being arranged to mesh with a gear wheel coupled to the said second holder, the gearing being such that the sum of the total angles through which the two holders turn is at least equal to 720°, a worm wheel which has its axis concentric with that of the sun gear wheels, means journaling said counter-shaft in said worm wheel and a worm arranged to mesh with and rotate said worm wheel to cause the counter-shaft to move in an orbital path.

70 9. In fuse-setting apparatus of the type having rotatable holders, and locating elements carried by said holders for respective engagement with the fixed and movable abutments on the body of a fuse, the combination with a planet gear train

including a driving member and two driven members, said driven members being respectively operatively connected to said holders to drive the latter in opposite directions, the operative connection between one of said driven gears and the associated holder comprising a second planet gear train including a normally stationary reactive member, and means for adjusting the position of said reactive member to advance or retract the associated holder with respect to the other holder prior to operation of said first planet gear train, thereby to predetermine the fuse-setting.

10. Fuse-setting apparatus having rotatable holders, locating elements mounted in said holders and adapted to engage with the fixed and movable abutments on the body of a fuse, means for causing relative rotary movement between the two said holders, said means comprising a differential gear, and driving means operative to drive one sun gear wheel of said differential gear, the second sun gear wheel being operatively connected to one only of said holders to drive the same in one direction, the planet carrier of the differential being operatively connected to the second of said holders to drive the same in the opposite direction.

11. Fuse-setting apparatus having rotatable holders, locating elements mounted in said holders and adapted to engage with the fixed and movable abutments on the body of a fuse, means for causing relative rotary movement between the two said holders, said means comprising a differential gear, driving means operative to drive one sun gear wheel of said differential gear, one of the holders being operatively connected to the second sun gear wheel so as to be driven in one direction thereby, the planet carrier of the differential gear being operatively connected to the second of the said holders to drive the same in the opposite direction, one of such operative connections comprising a train of gear wheels coupling one holder to its driving source in the differential, a pair of gear wheels of said train of different pitch diameter being mounted for orbital movement about the axis of rotation of the sun gear wheels to alter the relative angular positions of the said holders, and means to hold said orbitally mounted gear wheels in any desired orbital position.

VALENTINE PEARCE HARVEY.
